FLAME DETECTOR SYSTEM

John Thomas Hick, Malba, N. Y.

Application September 20, 1948, Serial No. 50,089

5 Claims. (Cl. 177—355)

1

This invention relates to flame detectors.

An object of this invention is to provide a flame detector or system which will detect the presence of flames at various spaced points, whereby to detect the spread of flame from one place to another.

Another object of this invention is to provide a flame detector system comprising a plurality of flame detector units and signals normally inoperative, and which will become operative when a flame contacts any one of the units, and means to put the unit which has been contacted by flame out of commission and to stop the signal from signalling so that should the flame contact another unit, the signal will again signal to indicate the spread of the flame.

Yet another object of this invention is to provide in a system of the character described, means to test the signal to see whether it is operative.

Yet a further object of this invention is to provide a strong, rugged and durable flame detector system of the character described, which shall be relatively inexpensive to manufacture, easy to manipulate, which shall be positive in operation, yet practical and efficient to a high degree in use.

Other objects of this invention will in part be obvious and in part hereinafter pointed out.

The invention accordingly consists in the features of construction, combinations of elements, and arrangement of parts, which will be exemplified in the construction hereinafter described, and of which the scope of invention will be indicated in the following claims.

In the accompanying drawings in which is shown various illustrative embodiments of this invention,

Fig. 1 is a front view of one of the flame detector units embodying the invention, with the front cover removed;

Fig. 2 is a cross-sectional view taken on line 2—2 of Fig. 1;

Fig. 3 is a cross-sectional view taken on line 3—3 of Fig. 2;

Fig. 4 is a front view of one of the flame detector units embodying the invention, mounted on a support;

Fig. 5 is a cross-sectional view taken on line 4—4 of Fig. 4;

Fig. 6 is an end view of one of said units;

Fig. 7 is a cross-sectional view taken on line 8—8 of Fig. 3; and

Fig. 8 is a wiring diagram illustrating a flame detector system embodying the invention.

2

Referring now in detail to the drawings, 10 designates the wiring diagram for the flame detector system embodying the invention. The system 10 comprises a plurality of flame detector units 11 which may be placed in various parts of a compartment, room or building, enough units being employed to give adequate protection. Each unit 11 comprises a metal casing 12.

Each casing 12 comprises a semi-circular top wall 13 and end walls 14 extending therefrom. It has a bottom wall 15. The end walls 14 are formed with aligned through openings 16 adjacent the bottom wall 15. Said casing has side walls 17 and 17a and is formed with a circular through opening 18. The axis of the opening 18 is at right angles to the axis of the openings 16.

The side wall 17a is formed with a substantially semi-circular flange 19. The flange 19 is formed with a plurality of screw threaded 20 through openings 20.

The top wall 13 is formed with a lug 22 having a through opening 23. The lug 22 extends across the width of the top wall. Said top wall is also formed with a lug 24 in alignment with the flange 19. The lug 24 is formed with a through opening 25, for the purpose hereinafter appearing. Extending down from the bottom wall 15 is a central lug 27 formed with a through opening 28 for the purpose hereinafter appearing. Extending from the end walls 14 are bosses 30 each formed at the top with a horizontal through opening 31. Extending from the bosses 30 are externally screw threaded tubular projections 32. The through openings 16 pass through the bosses 30 as well as the tubular extensions 32.

At one side of the semi-circular wall 13 is a lug 35 formed with a through opening 36 and disposed between the lug 24 and one end of the flange 19. At the opposite side of the wall 13 is a hook 37 which may be either integrally formed with the top wall, or may be attached thereto in any suitable manner.

Contacting the inner surface of the flange 19 is a semi-circular insulating plate 40. Plate 40 may be attached to the flange 19 by means of screws 41 which pass through the threaded opening 20 in said flange. The top edge of the insulating plate 40 is horizontal and at the level of the ends of flange 19. Attached to the inner side of the insulating plate 40 is a metal plate 42. Screwed onto said plate 42 is a binding post 43. Also fixed to said plate 42 is a spring clip 44. Also attached to the insulating plate 40 is a second metal plate 45 spaced and insulated from the plate 42. Plate 45 is formed with an

upstanding finger 47. Attached to the plate 45 is a spring clip 48. The finger 47 projects above the upper edge of the insulating plate 40.

Mounted on and between the spring clips 44 and 48 is a fuse 50 including a fuse element 51. The terminals for the fuse element 51 are fixed to the spring clips 44, 48 and to the metal plates 42 and 45 by screws 52 and 53, or in any other suitable manner.

Fixed within the opening 25 in the lug 24 is 10 a pin 55. Pivoted on the pin 55 is a lever 56 interconnected by a coil tension spring 57 to the opening 36 of the lug 35. The spring 57 interconnects an intermediate portion of the lever with the lug 35. The lever 56 is also interconnected to the hook 37 by a thread or filament 60 made of inflammable material, that is, material which is more sensitive to flame than to heat. Nylon or silk thread may be employed for this purpose, also any element such as strips or filaments of metal, cotton, wool, or plastic which will burn and break when contacted by flame.

It will be noted that the thread 60 retains spring 57 under tension. At the outer end of lever 56 is a lug 58. If the thread 60 were to burn by contact with flame, and break, the spring 57 will swing the lever 56 in a clockwise direction, looking at Fig. 3, so that the lug 58 will strike the finger 47.

Attached to the sides of the casings 12 are cover members 62. The cover members 62 are curved at the top and have a straight bottom edge 63, and the lower edges 64 at the sides are also straight, merging into the top curved edge 66. The cover members 62 are each formed in the upper half portions thereof with a plurality of slots or louvers 67. The side walls 17, 17a of the casing are formed with through openings 70 adjacent the bottom wall 15. The cover plates are attached to the casing by means of bolts 71 passing through the openings 23 and 70 of the casing. The flames may enter the casing through the louvers 67.

Each unit may be mounted on a support or bracket 74. The bracket 74 is attached to the casing by means of bolts 75 passing through the openings 28 and 31 of the casing.

A plurality of said units 11 may be interconnected by means of flexible conduits 76, such as "Bresel" cables. Attached to the ends of the conduits 76 are ferrules 77 crimped onto the cable. Each ferrule has a flange 78 contacting one end of the externally screw threaded portion 32 and is clamped thereto by means of a screw coupling 79. The wiring which interconnects the units passes through the conduits 76. The wiring diagram interconnecting the units 11 will now be described.

Extending through the casings and through openings 16 thereof, and the cables 76, is a wire 80. The wire 80 goes back and forth through the casings and the cables or conduits. The wire 80 is connected by wires 81 to the binding posts 43 so that fuses 51 are connected in parallel with each other. It will be noted that the levers 56 are all grounded as at 82 due to their connections to the metal casings 13. The levers 56 as well as the pins 55 on which they are mounted are made of electric conducting material.

The wire 80 entering the first casing 12 passes through all the casings and the conduits interconnecting them, and then goes back, as shown in Fig. 8 of the drawing. On any suitable bracket or support (not shown) may be mounted

an electric signal device 83, such as a lamp or bell, having terminals 84 and 85. The wire 80 has terminals 80a and 80b which may be mounted on the support or bracket on which the signal 83 is mounted. The terminal 85 is connected by wire 86 to the terminal 80a of the wire 80. The other terminal 84 is connected through wire 87 to one side of a battery or other source of electric power 88, the other side of which is grounded as at 89. On the support on which the signal 83 is mounted, is a push button switch 90 adapted to interconnect a pair of terminals 91 and 92. The terminal 92 is connected to the terminal 85 by wire 94. The terminal 91 is connected to the terminal 84 by wire 95. The push button 90 is normally open. When it is closed, the signal 83 is short circuited.

Terminal 80a is connected by wire 96 to a contact 97. Attached to the terminal 80b is 20 a manual switch arm 98 adapted to contact the terminal 97 in one position of the switch. Said switch 98 is adapted to swing into engagement with a second contact 99 grounded as at 100.

The operation of the flame detector system 25 embodying the invention will now be described. The various units 11 are placed at spaced points of an airplane engine cowling or at spaced points of any compartment, room, or on any apparatus wherever it is desired. Normally the test switch 30 98 is closed, that is, it engages the contact 97 and the push button switch 90 is open. In such condition the signal 83 will not be energized. However, if the switch 98 is moved into engagement with the contact 99, the circuit will be 35 completed to the signal 83 through ground 89, battery 88, wire 87, signal 83, wire 86, wire 80, switch 98, contact 99 and ground 100.

When the operativeness of the signal has been 40 tested and assured, the switch is again moved into engagement with the contact 97 and the signal will not be energized. However, should the filament or thread 60 of any unit be contacted by flame passing into the casing through louvers 67, the thread will burn and break and the spring 57 for that unit will swing lever 56 to cause the lug 58 to engage the finger 47, thus closing the circuit through the signal device 83 and the fuse 51 for that unit. The circuit is through ground 89, battery 88, wire 87, signal 83, wire 86, wire 80, wire 81, fuse 51, finger 47, lug 58, lever 56 and ground 82.

When the signal is energized, the operator may 55 cause CO₂ gas to enter the place where the units are located to extinguish the flame, or any other suitable flame or fire extinguishing method may be used. After steps are taken to extinguish the flame, the operator may close the normally open switch 90, causing the signal 83 to be short circuited and imposing full voltage on the fuse 51 in the unit with the broken thread 60. The fuse will blow. The push button is then released and again opens, and the circuit through the signal is then broken and said signal will again be deenergized. If, thereafter, the flame reaches 65 the thread of another unit and the thread burns and breaks, the signal will again be energized and the operator will know that the flame is spreading and will again apply the flame extinguishing steps.

If the signal does not again become energized, 70 it will indicate to the operator that the flame is not spreading. After one fuse is blown the signal device may be tested by means of test switch 98. It will now be understood that with 75 the blowing of a fuse the unit which was in the

fire area will be put out of commission, allowing the other detector units to be operative.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

It will now be understood that with the present system there will be no false alarm due to heat alone and when the signal actuates you can be sure that there is flame and hence fire.

Having thus described my invention, what I claim as new and desire to protect by Letters Patent of the United States is:

1. A flame detector system comprising a plurality of flame detector units, each unit comprising a contact, a fuse in series circuit with each contact, an electric signal device, means to connect said fuses in parallel with each other and each in series with said signal device, each unit including a movable contact, means to urge the movable contact of each unit into engagement with the first contact of said unit, means to retain the movable contact of each unit out of engagement with the first contact of said unit, said last means including a filament adapted to break upon burning by contact with flame to permit the urging means for said unit to move the movable contact into engagement with the first contact for completing the circuit to the electric signal device for energizing the same, and means to short circuit the electric signal device, each fuse being of such rating that it will blow when the signal device is short-circuited, and will not blow when the signal device is included in its circuit.

2. A flame detector system comprising a plurality of flame detector units, each unit comprising a fixed contact, a fuse in series circuit with each contact, an electric signal device, means to connect said fuses in parallel with each other and each in series with said signal device through common wiring, each unit including a movable contact, spring means to urge the movable contact of each unit into engagement with the fixed contact of said unit, means to retain the movable contact of each unit out of engagement with the fixed contact of said unit, said last means including a filament adapted to break upon burning by contact with flame to permit the spring means for said unit to move the movable contact into engagement with the fixed contact for completing the circuit to the electric signal device for energizing the same, each fuse being of such rating that it will blow when the signal device is short-circuited and will not blow when the signal device is included in its circuit, manual switch controlled means to short circuit the electric signal device, a second manual switch, means controlled by said last switch to energize said signal at will, to test the operativeness of said signal device and said common wiring, a casing for each unit, conduit means interconnecting said casings, and the wiring which interconnects said fuses and signal passing through said conduits.

3. A flame detector system comprising a plurality of flame detector units, each unit includ-

ing a filament which will burn by contact with flame, an electric signal, and means to actuate said signal when any of the filaments burn and break, said means including a fuse for each unit, means to connect said fuses in parallel circuit with each other and in series circuit with said signal, and means controlled by the breaking of each filament to complete the circuit for the fuse of the unit for said filament and the signal, and manual means to short circuit said signal, each fuse being of such rating that it will blow when the signal device is short-circuited, and will not blow when the signal device is included in its circuit.

15 4. A flame detector system comprising a plurality of flame detector units, each unit including a filament which will burn by contact with flame, an electric signal, and means to actuate said signal when any of the filaments burn and break, said means including a fuse for each unit, means to connect said fuses in parallel circuit with each other and in series circuit with said signal through common wiring, and means controlled by the breaking of each filament to complete the circuit for the fuse of the unit for said filament and the signal, and manual means to short circuit said signal, each fuse being of such rating that it will blow when the signal is short-circuited, and will not blow when the signal is in its circuit, and manual means to energize said signal and wiring at will.

20 5. A flame detector system comprising a plurality of flame detector units, each unit comprising a contact, a fuse in series circuit with each contact, an electric signal device, means to connect said fuses in parallel with each other and each in series with said signal device through a common wire, each unit including a movable contact, means to urge the movable contact of each unit into engagement with the first contact of said unit, means to retain the movable contact of each unit out of engagement with the first contact of said unit, said last means including a filament adapted to break upon burning by contact with flame to permit the urging means for said unit to move the movable contact into engagement with the first contact for completing the circuit to the electric signal device for energizing the same, each fuse being of such rating that it will blow when the signal device is short-circuited and will not blow when the signal device is included in its circuit, means to short circuit the electric signal device, a manual switch, and means controlled by said switch to energize said signal at will, to test the operativeness of said signal through said common wire.
